US00D819671S

(12) **United States Design Patent** (10) Patent No.: **US D819,671 S**
 Rajaraman et al. (45) Date of Patent: ** Jun. 5, 2018

(54) **DISPLAY PANEL WITH A VIDEO
PLAYBACK PANEL OF A PROGRAMMED
COMPUTER SYSTEM WITH A GRAPHICAL
USER INTERFACE**

(71) Applicant: **Google Inc.**, Mountain View, CA (US)

(72) Inventors: **Shivakumar Littoo Rajaraman**, San Francisco, CA (US); **Stein Eldar Johnsen**, Ranheim (NO); **Jonas Yngvesson**, Binz (CH); **Jasmine Kent**, Zurich (CH); **Elena Digor**, Thalwil (CH); **Jun Li**, Zurich (CH); **Matias Cudich**, San Francisco, CA (US)

(73) Assignee: **GOOGLE LLC**, Mountain View, CA (US)

(**) Term: **15 Years**

(21) Appl. No.: **29/575,418**

(22) Filed: **Aug. 24, 2016**

CLAIM

We claim the ornamental design for a display panel with a video playback panel of a programmed computer system with a graphical user interface, as shown and described.

DESCRIPTION

The FIGURE is a front view of a display panel of a video playback panel of a programmed computer system with a graphical user interface showing our new design.

The broken lines shown in the drawings illustrate portions of the graphical user interface that form no part of the claimed design.
